(57) **CLAIM**

The ornamental design for an EKG monitor, as shown and described.

DESCRIPTION

FIG. 1 is a perspective view of an EKG monitor;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a perspective view thereof in an alternative condition.

The broken lines in FIG. 3 are included for the purpose of illustrating portions of the EKG monitor that form no part of the claimed design.

1 Claim, 6 Drawing Sheets
